UNITED STATES PATENT OFFICE

ARCHIE W. PLATT, OF TOLEDO, OHIO, ASSIGNOR TO THE EDWARD FORD PLATE GLASS COMPANY, OF ROSEFORD, OHIO, A CORPORATION OF OHIO

GLASS-POLISHING APPARATUS

Application filed August 16, 1928. Serial No. 129,405.

This invention relates to apparatus particularly intended for grinding and polishing plate glass in a continuous manner.

In the grinding and polishing of plate glass by what is commonly referred to as a continuous process wherein a practically continuous strip of glass is passed beneath the grinding and polishing members, considerable difficulty has been experienced in keeping the felt covering the polishing blocks in proper surface condition to efficiently perform the intended function. The working felt surfaces of the blocks soon become coated with a hard glazed deposit of the polishing or abrading material which not only prevents the polishing or abrasive action taking place, but frequently results in scratching the finished or partly finished surface. Many means and methods have been used and practiced to overcome this objection, but so far as I am aware, without entirely satisfactory results. These old methods are expensive and cumbersome and result in considerable loss of time in the polishing process.

An object of the invention is the provision of a grinding and polishing means of the class described which will overcome the objections above noted, and will perform the grinding or polishing operations in a rapid and efficient manner.

Another object of the invention is the provision of simple and efficient means for intermittently cleaning and reconditioning the felt covering working surfaces of the abrading or polishing blocks without stopping the machine.

Other objects and advantages of the invention will be apparent from the following detailed description.

Figure 1 is a top plan view of an apparatus embodying the invention, with parts broken away; Fig. 2 is a cross-section thereof on line 2-2 in Fig. 1; Fig. 3 is an enlarged section on the line 3-3 in Fig. 2; Fig. 4 is a section on the line 4-4 in Fig. 3 with the split nut jaws closed; Fig. 5 is a similar section with the split nut jaws open; Fig. 6 is a top plan view of a polishing-unit transferring truck with the top frame part broken away; Fig. 7 is a longitudinal section on the line

7-7 in Fig. 1, and Fig. 8 is a side elevation of the parts shown in Fig. 7.

Referring to the drawings, 1-1 designate a plurality of pairs of transversely spaced main frame standards with the pairs spaced lengthwise of the machine and cooperating with each other to form a space or runway 2 longitudinally of the machine in which a conveyor, or movable tables 3 arranged in successive end abutting relation, are adapted to travel. These tables are intended to support the plate glass 4 to be ground or polished and are mounted on trucks 5, the wheels of which travel on rails 6 mounted lengthwise in the bottom of the runway 2. A bearing standard 7 is provided at the outer side of each standard 1, being tied thereto at its top by a cross-head piece 8. The standards 7 at one side of the machine cooperate with the adjacent standards 1 to form a space or runway 9 therebetween, while the standards 7 at the other side of the machine cooperate with the standards 1 at such side to form a space or runway 10. The runways 9 and 10 parallel the runway 2, and each has rails 11 forming a track on which one or more transfer trucks 12 travel.

The frame standards 1 of each pair are connected at each side thereof across the top portion of the runway 2 by a pair of upper and lower guide or track bars 13 and 14 respectively, which face the pair of corresponding guide bars on the adjacent side of the next pair of frame standards 1 in order and cooperate therewith to form guides 23 for the purpose hereinafter described. These guide bars, in the present instance, are of L-form and extend at their ends beyond the outer sides of the respective frame standards 1, and a short distance over the respective runways 9 and 10 for the transfer trucks 12.

In the practicing of my invention a plurality of rotary polishing units 15 are intended to travel in successive order across the top of the glass 4 on the table 3, being guided in such movement by one set of guide bars composed of upper and lower pairs of opposed bars 13 and 14, respectively, and to successively move onto the transfer truck 12 at one side of the machine and then be transferred

5 a distance lengthwise of the machine to enable it to be passed back across the table in the next associated set of guide bars 13, 14, and as each unit reaches the opposite side of the table 3 and passes on to the truck 12 at such side it is again transferred to and fed into and through the first mentioned set of 10 guide bars. During this cycle of movements of the polishing units the conveyor 3 carrying the glass 4 that is being acted on may be intermittently advanced through the runway 2 or may be run slowly and continuously through the runway, as may be desired, the speed of movement of the tables being suitable for the grinding or polishing action being performed.

15 Each polishing unit 15 includes a head 16 carried at the lower end of a vertical shaft 17 and a plurality (in the present instance 4) of runners or work coating blocks 18 carried by each head 16 for turning movements therewith and for rotary movements relative thereto, as well understood in the art. The blocks 18 usually have their working surfaces covered with felt.

20 Each shaft 17 is journalled in a carriage composed, in the present instance, of a body member 19, having at its upper end a cross-head 20, which travels in the upper cooperating set of guide bars 13, and at its lower end a similar cross-head 21, which is adapted to be guided by the lower cooperating guide bars 14 of a set, as best shown in Fig. 7. Each shaft 17 above its carriage is provided with 25 a sprocket-wheel 22, which, when the unit is in either guideway 23 is adapted to engage a cross-run of a drive chain 24, which operates when moved to impart rotary movements to the shaft 17, and the parts carried thereby. The chain 24 has a rectangular course of movement except that at one side of the runway 2 it is looped around a drive sprocket 25 mounted on a vertical shaft 26 that is connected through a set of bevel pinions 27 to a main drive shaft 28 extending 30 longitudinally over the machine frame. The chain 24 at the corners of its movement passes around guide sheaves 29 carried by bearing brackets 30 on the upper ends of the associated frame standards 1 at the respective sides of the frame. The shaft 26 is journalled in one of the brackets 30, and the drive shaft 28 is journalled in bearings 31 mounted on such bracket. The shaft 28 continues throughout 35 the length of the machine and has driving connection with the successive chains 24 of the machine the same as with the chain above mentioned. One cross-run of a chain 24 is intended to impart rotary movements to the 40 polishing units as they travel in one direction across the conveyor through one guideway 23, and the other cross-run of a chain is intended to impart similar rotary movements to the units of the same set as they travel in the opposite direction across the conveyor through

45 the other guideway 23. The cross-runs of the chain are positioned to engage the inner sides of all of the sprocket wheels 22 of a set so that the several units have rotation in the same direction imparted thereto in both directions of movement of the units across the conveyor.

50 The polishing units of each set have the respective movements imparted thereto across the conveyor by two screw shafts 32, 32^a one being provided with a right thread and associated with one cross-run of the set and the other being provided with a left thread and associated with the other cross-run of the set. These shafts are disposed at the outer sides of the respective cross-runs of the unit sets and between an associated pair of the guide bars 13 and 14. Each body member 19 of a unit carriage is provided with a pair of hinged cross-arms 33 forming half nuts or threaded jaws 34 at each side of their pivot, which jaws close and open together and are adapted to receive and have threaded engagement with one or the other of the screw shafts 32, 32^a as the units pass through one or the other of the associated guideways 23.

55 In other words, when the units are traversing one guideway 23 the jaws at one end of the arms 33 are adapted to have threaded engagement with one of the shafts 32, 32^a, and when traversing the other guideway the jaws at the opposite ends of the arms 33 are adapted to have threaded engagement with the other of the shafts 32, 32^a. The arms 33 are connected and operate in the manner of scissors and are normally held closed by the action of springs 35 (Figs. 4 and 5). The arms 33 are mounted crosswise of each carriage body 19 in a loop 36 provided on one side thereof and the ends of the arms project without the loop in position to engage the screw shaft which is adjacent to the respective cross-arm of the units. The shafts 32, 32^a extend entirely across the machine and are journalled at their ends in respective 60 bearings 37 provided on the adjacent frame standards 7, and each shaft at one end is provided with a worm wheel 38 in mesh with a worm 39 on a drive shaft 40 disposed lengthwise of the machine at one side thereof and journalled in bearings 41 provided on the frame standards 7 at the side of the machine therewith. The speed of driving and the pitch of the threads of the shafts 32 are such as to impart the desired speed of movement to the units 15 across the polishing table. The speed of movement is preferably slow.

65 Each transfer table 12 is provided at its outer side with a unit carrying-head 42 having forked arms 43 and 44 projecting inwardly in vertically spaced relation from the upper end portion thereof and adapted to be placed by movements of the truck and to register respectively with the upper and lower guide bars 13 and 14 of either guideway 23.

It is apparent that each polishing unit carriage as it passes from the leaving end of one guideway 23 enters the registering carrying arms 43 and 44 of a transfer truck and that when the truck has been moved to place its forked arms into register with the entering end with the other guideway 23 the unit carriage may pass from the truck into such guideway.

When a unit 15 has been moved into proper position over a truck 12 from the leaving end of a guideway 23, the split nut 34 thereof is caused to release the engaged screw shaft 32, 32^a by reason of the outer wedge 15 end of a stationary arm 45 entering between the slightly spaced lips 46 on the arms 33 at the outer sides of split nut members thereof, as shown in Fig. 2. A wedge arm 42 projects toward the leaving end of each guide 23 from an adjacent frame standard 7.

If desired, the runners or polishing blocks 18 of a unit when over a truck 12 may rest on a plurality of small rollers 47 mounted in the top of the truck with their axes radially disposed. The purpose of the rollers 47 is to facilitate the rotation of the runners during such time as they are partially carried by the glass on the conveyor or polishing table and partially by the transfer truck.

In the top of each truck 12 is mounted a scraping edge 48 disposed at the side of the truck adjacent to the conveyor and adapted to have scraping coaction with the working faces of the runners 18 as they pass thereover so as to clean and condition the felt covering such surfaces. This is an important feature of the machine as it enables the polishing surfaces of the runners to be automatically cleaned and reconditioned after each polishing movement across the polishing table. This reconditioning takes place during the movement of a polishing unit over a transfer truck and before the sprocket wheel 22 of the unit has been disengaged from the driving chain 24, which takes place when the unit has moved a predetermined distance over the truck. During the time the unit is at rest on a truck any necessary operations may be performed on the felt runner blocks or other parts of the unit.

In the operation of the machine the conveyor 3 with glass thereon is fed slowly through the machine and the polishing units are successively fed across the conveyor at 55 right angles to the direction of travel of the same and at a predetermined speed by the engagement of the split nut of each unit with the associated screw shaft 32, 32^a. The units as they leave either guideway 23 pass onto the registering transfer truck 12, which is then moved in the present instance, by hand into register with the other guideway and the nut then placed into engagement with the worm shaft of such guideway so that the unit 60 is caused to again travel across the conveyor.

During the travel of the polishing units across the table the sprockets 22 thereof are in engagement with the drive chain 24, thereby imparting revoluble polishing movements to the runners 18. As soon as the runners of a unit have passed from engagement with the glass on the table the sprocket 22 of the unit leaves the chain 24 so that the rotation of the runners is stopped, and when the unit has reached final position on the truck the associated split 75 nut 34 will have been opened by the action of the adjacent wedge arm 45 to release the screw shaft. The working surfaces of the runners while still revolving engage the scraper 47 on the truck top and are thereby 80 cleaned and reconditioned preparatory for their next polishing travel across the glass.

It is old to polish glass by causing the polishing heads to travel lengthwise of or parallel with the movement of the table. In such case, however, it is found that the glass sheets do not get as much polishing effect on the edges as they do in the center, resulting in a condition known to the trade as "short-finished". With the present method, 85 wherein the polishing heads or units travel across the width of a table and continue their rotation until they have passed from the table at the side, the objectionable condition above noted is largely overcome, resulting in a considerable saving of the waste occasioned in the other method by cutting off the "short finished" edge portions of the sheet which usually amounts to a strip several 90 inches wide at each side of the sheet.

While I have particularly described only one set of polishing units, transfer trucks and associated driving parts, it is apparent that as many of such sets of parts as desired may be added in successive order to the machine 100 to accomplish the necessary grinding or polishing of the glass sheets as they are passed continuously through the machine from one end to the other thereof.

It will be understood that the reference 110 herein to plate glass applies to and includes all kinds of sheet glass which is adapted to be ground or polished and is not restricted to that kind of glass which is commonly referred to in the trade as "plate glass"; also that the term "polishing", as used herein, is intended to include any abrasive action applied to the glass plates whether the same be for grinding or for polishing the plates, and that while the machine contained herein is intended primarily for polishing, strictly speaking, glass plates or sheets, it may also be used for the grinding of the surfaces of such sheets.

I wish it understood that my invention is not limited to any specific construction, limitations and changes without departing from the spirit of the invention.

Having thus described my invention, what 120

I claim as new and desire to secure by Letters Patent is:

1. In a machine of the class described, a conveyor for supporting plate glass and having a defined path of movement, a polishing unit having two defined paths of movement across the conveyor transverse to the conveyor movement, means for transferring the unit from one path of transverse movement to the other, and separate means for feeding the unit from one side to the other of the conveyor in the path of movement in which disposed.
2. In a machine of the class described, a conveyor for supporting plate glass and having a defined path of movement, a polishing unit having two defined paths of movement across the conveyor transverse to the conveyor movement, means for transferring the unit from one path of transverse movement to the other, separate means for feeding the unit from one side to the other of the conveyor in the path of movement in which disposed, and means for rotating the unit during its movements across the conveyor.
3. In a machine of the class described, a conveyor for supporting plate glass and having a defined path of movement, a polishing unit having two defined paths of movement across the conveyor transverse to the conveyor movement, means for transferring the unit from one path of transverse movement to the other, separate means for feeding the unit from one side to the other of the conveyor in the path of movement in which disposed, means forming a part of the transferring means for conditioning the working surface of the unit at an end of a path of movement, and means for causing relative rotation between the conditioning means and unit.
4. In a machine of the class described, a conveyor for supporting plate glass and having a defined path of movement, a polishing unit having two defined paths of movement across the conveyor transverse to the conveyor movement, means for transferring the unit from one path of transverse movement to the other, separate means for feeding the unit from one side to the other of the conveyor in the path of movement in which disposed, means for rotating the unit during its movements across the conveyor, and means forming a part of the transferring means for conditioning the working surface of the unit at an end of each path of movement while the unit is rotating.
5. In a machine of the class described, a conveyor for supporting plate glass and having a defined path of movement, means forming two guideways across the conveyor transverse to its path of movement and open at their ends, a plurality of polishing units successively movable through the guideways from one end to the other thereof and from the outlet end of each guideway, means for

receiving each unit as it passes from the outlet end of one guideway and operable to transfer it to the entrance end of the other guideway, and separate means for feeding the units through each guideway in polishing engagement with the glass on the conveyor.

6. In a machine of the class described, a conveyor for supporting plate glass and having a defined path of movement, means forming two guideways across the conveyor transverse to its path of movement and open at their ends, a plurality of polishing units successively movable through the guideways from one end to the other thereof and from the outlet end of each guideway, means for receiving each unit as it passes from the outlet end of one guideway and operable to transfer it to the entrance end of the other guideway, means for feeding the units through each guideway in polishing engagement with the glass on the conveyor, and means for automatically releasing the driving engagement of said feeding means with each unit as the unit reaches a predetermined point on said receiving means.

7. In a machine of the class described, a conveyor for supporting plate glass and having a defined path of movement, means forming two guideways across the conveyor transverse to its path of movement and open at their ends, a plurality of polishing units successfully movable through the guideways from one end to the other thereof and from the outlet end of each guideway, means for receiving each unit as it passes from the outlet end of one guideway and operable to transfer it to the entrance end of the other guideway, separate means for feeding the units through each guideway in polishing engagement with the glass on the conveyor, and means to impart polishing rotation to parts of the units as they travel across the conveyor.

8. In a machine of the class described, a conveyor for plate glass to be polished having a defined path of movement, a truck mounted for movement at each side of the conveyor and parallel with its line of movement, two guides extending over the conveyor transversely thereof and in spaced relation longitudinally of the conveyor movement and being open at each end, a plurality of polishing units guided for successive movements across the conveyor by the guides, and having rotary glass polishing means, means for feeding each unit through a guide in which disposed, and on to the adjacent truck at the outlet end of the guide to permit the unit to be transferred to the inlet end of the other guide by a movement of the truck, and means common to both guides for driving the rotary polishing means of the units during their passage across the conveyor.

In testimony whereof I have hereunto signed my name to this specification.

ARCHIE W. PLATT. 130
